UNITED STATES PATENT OFFICE.

CHARLES T. CLARK, OF PHILADELPHIA, PENNSYLVANIA.

DESIGN FOR A NECKTIE HOLDER AND FASTENER.

SPECIFICATION forming part of Design No. 30,611, dated April 25, 1899.

Application filed March 13, 1899. Serial No. 708,966. Term of patent 7 years.

To all whom it may concern:

Be it known that I, CHARLES T. CLARK, a citizen of the United States, residing at the city of Philadelphia, in the county of Philadelphia and State of Pennsylvania, have invented and produced a new and original Design for a Necktie Holder and Fastener, of which the following is a specification, reference being had to the accompanying drawings, forming part hereof, in which—

Figure 1 is a front elevational view of the holder and fastener for neckties of the design of my invention. Fig. 2 is a side elevational view on the line $x-x$ of Fig. 1, and Fig. 3 is a top or plan view of the device of my invention.

The leading feature of my design consists of the shape or configuration of the device, as hereinafter described.

In the drawings, A represents a substantially elliptical-shaped vertical loop having a narrow throat about the free ends of said loop,

which free ends are curved, as at a and a' , and merge into thickened tapering arms a^2 and a^3 , the extremities of which at a^4 and a^5 are bent at substantially right angles into horizontal extensions b and b' , and which extensions terminate in downwardly-depending tapering arms or wings c and c' , as clearly illustrated in Fig. 1 of the drawings.

Having thus described my invention, what I claim as new, and desire to secure by Letters Patent, is—

The design for a necktie holder and fastener, as shown and described.

In testimony whereof I have hereunto set my signature in the presence of two subscribing witnesses.

CHARLES T. CLARK.

Witnesses:

J. WALTER DOUGLASS,
THOMAS M. SMITH.
